FURNACE FOR PRODUCING WOOD CHARCOAL

Curt Meyer, Buenos Aires, Argentina

Application December 22, 1943, Serial No. 515,293
In Paraguay November 17, 1943

5 Claims. (Cl. 202—89)

This invention relates to the production of charcoal, and particularly to a new furnace for the production of wood charcoal.

Several charring methods are known, which have been improved with the course of time so as to produce satisfactory results relative to the old system based on mud covered piles of wood billets. However, the general charring process is still slow, and particularly the subsequent cooling which requires a period of around four days.

Also, notwithstanding the improvements made, the methods and furnaces used for this purpose have several drawbacks which render the exploitation difficult, particularly in view of the fact that due to the manner in which the air admission holes are arranged and the manner in which the charge is kept in the furnace, the chambers are exposed to weather conditions and affected by wind, rain and low temperatures, to the extent that in some cases and zones it is only possible to char during certain seasons of the year.

Also, a close control should be kept of the furnace damper, as otherwise the charcoal might be reduced to ashes. On the other hand, in order to char with the known methods and furnaces, the wood should be well stationed as otherwise, if green or recently cut wood is used, very poor results will be obtained due to the extraordinary evaporation which might cause explosions which will alter the chamber walls as well as the auxiliary elements thereof.

The present invention overcomes the above mentioned drawbacks by providing two or more chambers so arranged that after the charring is completed in one chamber, the cooling will be obtained through absorption of heat by the batch in the other chamber or chambers. For this purpose, intercommunication is established therebetween so that by radiation or thermosiphon the heat will be transmitted sufficiently to obtain a fast drop of the temperature within the chamber containing the charred wood, while at the same time the other chamber or chambers will acquire temperatures capable of further drying the wood and causing a semi-distillation sufficient to char the wood in a short time during the subsequent cycle.

In carrying out the present invention, a double furnace formed by twin chambers is preferably used, said chambers communicating with each other at the top and at the bottom, and being provided with dampers and means for facilitating the handling thereof so that while the wood billets are being charred in one chamber, the other chamber will remain as an intermediary chamber

so that the draft towards the chimney will preheat the charge or batch to be charred in the subsequent cycle. Once the charring has been completed in the first chamber, the general inlets and outlets are closed and free communication is established between both chambers so that an exchange will be produced by thermosiphon, thereby causing the quick cooling of the charred wood, while at the same time taking advantage of the heat to further dry and condition the wood in the other chamber to be charred during the next cycle.

Apart from the above, the invention contemplates other objects, among which is the obtaining of a maximum yield, not only due to the development of the process itself, but also to the fast manner in which the cooling step takes place, which renders it possible to operate at the rate of more than one complete cycle per day, since this step can be completed in a period of from seven to ten hours.

A further object of the invention is to operate in an alternative manner with the two chambers, so that the work may be carried out in a substantially continuous manner for production on a large scale. For this purpose, while the charring is taking place in one chamber, the other chamber will remain as a secondary chamber or the conditioning of the batch therein, and once the first cycle is completed, the action of the chambers is reversed.

A still further object of the invention is to provide a furnace which will enable the satisfactory charring of fresh cut wood, inasmuch as the pre-conditioning mentioned above will dry same, thereby placing it in condition for charring.

A still further object of the invention is to obtain a high yield of wood charcoal of a homogeneous quality, suitable for different industries, as well as for domestic use.

A still further object of the invention is to provide apparatus for charring wood which will involve an economy in the general exploitation, not only due to the high yield but also to the low labour costs involved in view of the simple operation of the furnace.

A further object of the invention is to provide apparatus which will be safe in operation and eliminate danger of burning the wood charged in the chambers.

A still further object of the invention is to provide a furnace which may be readily taken apart, transported and reassembled.

A still further object of the invention is to

provide means for collecting tar and crude acetic acid as by-products of the distillation.

Other objects and advantages of the invention will become apparent from the course of the following specification, when read in conjunction with the accompanying drawings, illustrating by way of example two preferred manners of carrying out the charring process.

In the drawings:

Fig. 1 is a sectional view of the charring furnace, taken along the line N—N of Fig. 2.

Fig. 2 shows partial cross-sectional plan views of the same furnace.

Fig. 3 is a sectional view of the furnace, taken along the line S—S of Fig. 2, showing all the air intakes and outlets in closed position, after the completion of the charring operation in one of the chambers; and

Fig. 4 shows a somewhat modified form of furnace wherein each chamber is provided with a chimney.

The same reference characters are used to indicate like or corresponding parts or elements throughout the drawings.

As may be seen in Figs. 1, 2 and 3, the furnace comprises twin chambers *a* and *b* adjacent to each other and having a common wall *1* the central portion of which is provided with a chimney *c* which is also common to both chambers. Thus, each chamber is provided with an opening having a grid *3*, and since the chambers are to be used alternately, each opening *2* is provided with a gate *4* slidably mounted on vertical guides *5*, and as clearly shown in Figs. 1 and 3 said chimney *c* terminates with a hinged cover *6* actuated by means of a cable *8* guided on a sheave *9*.

Each of the chambers *a* and *b* are provided with auxiliary sets of air intakes *10* having hinged covers *11* and capable of being tightly closed after the admission of a certain amount of air necessary for carrying out the charring process.

Each of the chambers *a* and *b* is provided with a fireplace *12* constituted by passages having a slightly sloped bottom and located against the wall *1*, and as clearly shown in the drawings, said fireplaces *12* are provided with a plurality of air intakes *13* starting at the underground channel *14*.

Access to fireplaces *12* is provided by means of rear mouths *15*, having tight closing covers *15'*, of the respective chambers *a* and *b*, said fireplaces being capable of receiving cages *16* made of iron or other suitable material and housing a charge of coal and wood for starting the firing of the furnace, since said fireplaces have open fronts leading to the interior of the furnace containing the wood billets *17*.

Each chamber *a*, *b* is provided with a plane *18* forming a step with the floor *19* and formed by a slab supported by partitions *20*. Said plane *18* is kept in spaced relation to the slab *19*, thereby constituting, underneath the slabs of plane *18*, a plurality of conduits *21* extending throughout the width of the chamber and sloping towards the middle line of the furnace where, by means of passage *22*, the conduits *21* of the chambers communicate with each other, as graphically shown in Figs. 1 and 3; thus, it is possible to establish a connection between chambers *a* and *b* through said conduits *21* and passage *22*.

Passage *22* is provided with a container *23* for collecting tar and crude acetic acid as by-products of the distillation.

Apart from the intercommunication through

passage *22* connecting said conduits *21*, communication between both chambers may be established by means of a passage *24* located at the upper portion, as shown in Figs. 2 and 3, said passage being in turn provided with a gate *25* which should be kept closed during the charring operation. As will be explained hereinafter, said gate *25* should only be opened after completing the charring operation in one chamber and for the purpose of cooling the furnace by thermosiphon.

Said chambers *a* and *b* are provided with doors *26* of a size sufficient to readily allow the charging of wood and the removal of the charcoal resulting from the process; however, said doors should be provided with means to enable a tight closure thereof during the operation of the furnace.

Said underground channel *14* is provided with a general opening *14'* having a tight closing hinged cover *27*, as shown in Fig. 2.

In the embodiment of Fig. 4, chambers *a* and *b* are of the usual type having air intakes *28* and a corresponding closure *28'*, and as may be seen from the drawings, each chamber comprises a chimney *29* having a closing gate *30*.

The lower portion of chambers *a* and *b* communicates with conduit *31* having a gate *32*, while the upper portion of said chambers communicates through a conduit *33* also provided with a gate *34*.

Both the furnace shown in Figs. 1, 2 and 3 and that illustrated in Fig. 4, are provided with pyrometers *35* for the purpose of controlling the firing process.

Operation

In order to char with the furnace shown in Figs. 1, 2 and 3, both chambers *a* and *b* are charged with wood billets. If it is desired to first operate with the chamber *a*, the gate *4* of opening *2* in said chamber *a* should be closed, while gate *4* of opening *2* in chamber *b* is opened as shown in Fig. 1.

Cover *27* for the admission of air through mouth *14'* providing access to channel *14* of air intakes *13* corresponding to fireplaces *12* should also be opened, and cover *6* of draft chimney *c* should also be in open position as indicated in Fig. 1, thus remaining as an outlet for chamber *b* serving in this instance as intermediary to chamber *a*. Gate *25* should be kept closed.

Cover *15'* of chamber *a* (Fig. 2) is opened and cage *16* containing the necessary fire for starting the charring operation is introduced through mouth *15*. As mentioned hereinbefore, said cage is placed in the fireplace *12* so that after closing the mouth *15* by means of cover *15'* the furnace will remain in operating condition.

The fire of the fuel in cage *16* located within the fireplace *12* of chamber *a* will extend to the wood billets *17* constituting the charge of said furnace, thereby producing the combustion with the draft as indicated by the arrows in Fig. 1, viz., after the revolution in chamber *a*, the combustion gases will flow through conduit *21* of chamber *a*, passage *22* and conduits *21* in chamber *b*, thereby entering the latter where they will infiltrate through the wood billets *17* until they reach the opening *2*, from where said gases will pass to chimney *c* and through same to the atmosphere.

The heat of said gases will cause a previous semi-distillation in the billets *17* charged within chamber *b*, so that as the charring of the billets *17* and chamber *a* proceeds, the billets *17'* of

chamber *b* will be conditioned for the subsequent charring thereof.

The charring process is controlled by means of pyrometers 35 and other instruments which may be applied to the intakes 10 which in turn serve as windows, and once the charring process has reached a critical point, the main intakes 13 are closed by closing opening 14' by means of cover 27, so that upon opening the inlets 10, the ignition diffusing step will be initiated, since due to the change in position of the air intake, there will be a gradual lowering of the mass of fire in the charge in chamber *a*. Thereafter, the gradual closure of covers 11 will initiate a step which could be termed of "cooking" of the entire mass and in which the charring is completed, not only of the material comprised in the main direction of the ignition course aided by the draft, but also of that corresponding to the corners of said chamber *a*, as due to the lack of a free draft, the heat is diffused in a balanced and substantially distributed manner.

After this "cooking" period, cover 6 of chimney *c* should be closed, and also gate 4 of opening 2 corresponding to chamber *b*, so as to block any possible exhaust of valuable gases and keep both chambers tightly closed.

Throughout the process, the tar and acetic acid as by-products of the distillation, will run on the inclined floor 19 and be collected in collector 23.

The opening of gate 25 as shown in Fig. 3, will initiate the process of cooling the material in the furnace, which takes place in a substantially quick manner, due to the fact that upon opening the gate 25, both chambers *a* and *b* will communicate by means of passage 24 both from the top and the bottom portions, as shown in Fig. 3, whereby the heat of the material within chamber *a* will pass to that in chamber *b* as shown by the arrows in Fig. 3, in a closed thermosiphon circuit with return by means of conduits 21 and passage 22.

During this cooling period, the material 17' in chamber *b* will absorb the heat in chamber *a* in such a manner that the conditioning thereof will assume the nature of a semi-distillation, ready for charring in the subsequent cycle through a brief combustion process of less than 10 hours.

In this manner, the cooling may be obtained in a period of approximately 10 hours, so that after same has been completed, gates 25 of conduits 24 should be closed, and the doors 26 of chamber *a* opened so as to withdraw the charcoal resulting from the operation and to recharge same with wood billets.

After recharging with wood billets, mouth 14' is opened by lifting the cover 27, whereby the furnace will remain in the conditions shown in Fig. 1, with the difference that the gate 4 of mouth 2 corresponding to chamber *b* should remain closed, while gate 4 corresponding to chamber *a* should remain open, as in this instance chamber *b* will act as primary chamber, while chamber *a* will remain as secondary chamber. A cage 16 containing burning fuel should be inserted through mouth 15 of chamber *b*, so as to initiate the combustion of the preconditioned material in chamber *b* which is readily charred, with draft through conduits 21 and passages 22, that is to say, with the intervention of chamber *a* through which the combustion gases will circulate before being exhausted through chimney *c*.

As in the previous cycle, once the critical point is reached, the main intake 14' is closed and the air intakes 10 are opened so as to reduce the fire

in chamber *b*, whereafter the covers 11 are gradually closed so that the material will start a "cooking" period for the purpose of obtaining a complete and uniform charring. Finally, upon closing all gates and intercommunicating both chambers, the opening of gate 25, will initiate the cooling process in which by thermosiphon the heat will pass from one chamber to another, with the consequent advantage of the heat for conditioning the secondary chamber.

In the case of the furnace shown in Fig. 4, the charring of the material 17 in chamber *a* will take place in the usual manner, by closing gates 32 and 34 and opening the covers of air intakes 28 and draft gate 30.

After completing the charring operation in the usual manner, covers 28' and gate 30 should be closed, while the opening of gates 32 and 34 will communicate chamber *a* with chamber *b*, containing a charge of wood billets. Said chamber *b* should also be closed.

After communicating both chambers *a* and *b* through conduits 31 and 33, the heat of the charge in chamber *a* will be greatly absorbed by the charge in chamber *b*, either by radiation or by thermosiphon, thereby obtaining a substantially fast cooling of the charred charge in chamber *a* and the advantageous use of the heat for further drying and conditioning the wood in chamber *b*.

After the completion of the cooling process, gates 32 and 34 are closed and the charred charge in chamber *a* is removed and a fresh charge of wood billets placed therein.

The charge 17', already conditioned in chamber *b* is in turn ignited for charring in the usual manner but in a short period of time, since said conditioning involves a previous semi-distillation greatly reducing the duration of the charring step itself.

After completing the charring of the wood in chamber *b*, the air intakes and draft thereof are closed (covers 28' and gate 30), thereby initiating the cooling process, for which purpose gates 32 and 34 are opened so as to communicate with chamber *a* by means of conduits 31 and 33, so that the heat will be absorbed by the charge in the latter chamber.

Summarizing, the process for the production of wood charcoal is carried out with two or more charges of wood so that after charring one charge, the cooling of said charge will take place by transmitting the heat to the other chamber so that the charge to be subsequently charred will absorb the heat of the charred wood and at the same time obtain a quick cooling of the charred material. The heat absorbed by the chamber or chambers containing uncharred wood will condition the latter, ready for subsequent charring and cooling in the same manner.

It is evident that in carrying the invention into practice, several modifications, alterations and changes will occur to those skilled in the art, without departing from the scope of the present invention as clearly set forth in the appended claims.

I claim:

1. A wood charring furnace comprising twin charring chambers communicating with each other both at the top and at the bottom thereof, a gate for closing at least the communication at the upper portion of said chambers, said chambers having air intakes with corresponding dampers a fireplace in each chamber for initial ignition, said chambers having a chimney and means for closing the draft to said chimney and

a cover for closing said chimney, said chambers having a floor sloping towards a collector for by-products, said floor, by means of a slab supported between partitions, forming conduits leading towards the middle line and having a common intermediate passage, the conduits of both chambers communicating with each other.

2. A wood charring furnace comprising twin charring chambers communicating with each other both at the top and at the bottom thereof, a gate for closing at least the communication at the upper portion of said chambers, said chambers having air intakes with corresponding dampers a fireplace in each chamber for initial ignition, said chambers having a chimney and means for closing the draft to said chimney and a cover for closing said chimney, said fireplaces constituting passages each having an intake provided with a cover, with each passage provided with an underground admission, said passages opening towards the middle of the furnace and being adapted to receive fuel holding cages for the initial combustion of the charge.

3. A wood charring furnace as claimed in claim 2, wherein said fireplaces are provided with a plurality of auxiliary intakes having a plurality of tight closing covers.

4. A wood charring furnace comprising twin

charring chambers communicating with each other both at the top and at the bottom thereof, a gate for closing at least the communication at the upper portion of said chambers, said chambers having air intakes with corresponding dampers a fireplace in each chamber for initial ignition, said chambers having a chimney and means for closing the draft to said chimney and a cover for closing said chimney, each of said chambers having an opening leading to a common chimney and provided with a closing gate, said chimney having a cover and means for actuating said cover.

15 5. A wood charring furnace comprising twin
charring chambers communicating with each
other both at the top and at the bottom thereof,
a gate for closing at least the communication at
the upper portion of said chambers, said chambers
having air intakes with corresponding damp-
ers 20 a fireplace in each chamber for initial igni-
tion, said chambers having a chimney and means
for closing the draft to said chimney and a cover
for closing said chimney, said chambers being
adjacent the upwardly located communication,
said chambers being arranged wholly beyond and
25 on opposite sides of the chimney.

CURT MEYER.
